Primary Examiner — George D Kirschbaum(74) *Attorney, Agent, or Firm* — Suzanne Kikel(57) **CLAIM**

The ornamental design for an emergency vehicle warning device, as shown and described.

DESCRIPTION

FIG. 1 is a front perspective view of the emergency vehicle warning device.

FIG. 2 is a front elevational view thereof.

FIG. 3 is a rear elevational view thereof.

FIG. 4 is a top plan view thereof.

FIG. 5 is a bottom plan view thereof.

FIG. 6 is a left side view thereof; and,

FIG. 7 is a right side view thereof.

In the drawings, the broken line showing of an electrical cord, suction cup, and lettering depicts environmental subject matter and forms no part of the claim.
